(57) **CLAIM**

The ornamental design for a watch bezel, as shown and described.

DESCRIPTION

This application is related to and claims priority from earlier filed U.S. patent application Ser. No. 10/360,781, filed Apr. 1, 2003.

FIG. 1 is a front perspective view of a flashlight bezel, showing our new design;

FIG. 2 is a top plan view thereof;

FIG. 3 is a bottom view thereof;

FIG. 4 is a front view thereof;

FIG. 5 is a rear view thereof;

FIG. 6 is a right side view thereof;

FIG. 7 is a left side view thereof; and,

FIG. 8 is an additional top plan view of our design of FIG. 1.

The features depicted in broken lines in FIGS. 1 and 8 have been shown for illustrative environmental purposes only and form no part of the claimed design.
